TUBULAR LAMP RETAINING DEVICE

Selden Bradley Sanford, Yonkers, N. Y., assignor
to Otis Elevator Company, New York, N. Y., a
corporation of New Jersey

Application May 21, 1941, Serial No. 394,425

3 Claims. (Cl. 173—328)

The invention relates to retainers for tubular electric lamps, especially fluorescent lamps used for lighting.

Tubular fluorescent lamps are mounted on fixtures having brackets at each end for receiving the ends of the lamps. The lamp fixtures are usually mounted horizontally overhead with the lamp holder brackets extending downwardly. Each end of the lamp has two pins, connected to the lamp heater element, which are adapted to engage spring contacts in the brackets to complete the lamp circuits. Slots are provided in the faces of the brackets into which the pins are slid in mounting the lamp in the fixture. Usually these slots are vertical and connect with annular slots which form sockets. Upon the pins coming opposite the annular slot as the end of the lamp is inserted in its socket, the lamp is turned, moving the pins in the annular slot into position engaging the spring contacts. The spring contacts are formed in such way that they exert a force on the pins to hold the lamp in position. However, it sometimes happens that the ends of the lamp come out of their sockets, as for example, due to improper mounting of the brackets or the jarring of the lamps out of position by vibration, with the result that the lamp falls and breaks. Also, the lamp in falling may strike and injure someone.

The object of the invention is to provide retainers for lamps of the above character which insure holding the lamp in its fixture should one or both its ends come out of their sockets.

The invention involves the provision of a retaining clip for each end of the lamp pivotally mounted on the lamp bracket which is automatically held in released position when the lamp is not in place but which when the lamp is inserted in its sockets springs into retaining position automatically upon being swung over the end of the lamp and remains latched there. In carrying out the invention according to the arrangement which will be described, the clip is U-shaped with the yoke fitting under the end of the lamp. The upper ends of the clip are bent inwardly and extend into apertures in the sides of the bracket to form a pivotal mounting. Between the yoke and the ends of the wire, the clip is bent inwardly to form lobes, the distance between the lobes being less than the width of the bracket. The clip is formed of spring wire so that when it is pulled outwardly about its pivot to disengage the end of the lamp, the lobes engage the sides of the bracket to hold the clip in released position. To latch the end of a lamp in position,

the clip is pulled forward and as it swings about its pivot the lobes move off the sides of the bracket snapping the clip into and latching it in retaining position.

5 A general idea of the invention, the mode of carrying it out which is at present preferred, and various features and advantages thereof will be gained from the above statements. Other features and advantages of the invention will be apparent from the following description and appended claims.

In the drawing:

Figure 1 is a schematic representation in side elevation and with parts in section of a tubular fluorescent lamp mounted in a fixture embodying the invention;

Figure 2 is a fragmental detail in perspective of the end of the lamp latched in position in one of the lamp holder brackets of Figure 1, and,

Figure 3 is a similar view in perspective with the lamp removed showing the lamp holder bracket with the clip in released position.

Referring first to Figure 1, a tubular fluorescent lamp, designated 10, is mounted in lamp holder brackets 11 and 12, one at each end of the lamp. These brackets extend downwardly from a casing 13. Each bracket is secured to the casing by a screw 14 extending through a slot in the base 15 of the bracket into a cross-bar 16 secured to the sides of the casing. Referring also to Figure 3, each bracket has a circular opening 17 formed in the face thereof. A circular lug 18 formed on the back of the bracket extends into the circular opening and is concentric therewith, forming an annular slot. Spring contacts 20 and 21 are arranged in the circular opening beneath the face of the bracket. These spring contacts are arranged one on each side of the lug 18 with respect to the vertical center-line. Each spring is bent at an angle at the point 19 and is formed with a lip 22 at its lower end. A vertical slot 23 extends upwardly from the lower end of the bracket into the circular opening 17 and across the face of the lug 18. In inserting the end of the lamp in its socket, the pins 24 on the end cap 25 of the lamp are aligned with the vertical slot 23 and are slid upwardly therein until they come opposite the top and bottom of the annular slot. When this point is reached the lamp is turned so that one pin is swung under one spring contact and the other pin under the other spring contact, the lamp being turned at an angle of 90 degrees so as to place the pins at the angle points 19 of the spring

contacts so that these contacts will hold the lamp in turned position.

To prevent the falling of the lamp in the event that either end should come out of its socket, each bracket is provided with a retaining clip 30. This clip is U-shaped with the yoke 31 of the U extending under the end of the lamp as shown also in Figure 2. The yoke is of a diameter to fit in the groove 32 provided in end cap 25. Near the top of the clip at the points 33, the legs of the U are bent backwardly away from the end of the lamp and the ends 34 of the clip are bent inwardly at right angles to extend into apertures 35 provided in the sides of the bracket to form a pivot. Just below the points 33 and in front of the face of the bracket, the legs are bent inwardly to form lobes 36, the distance between the lobes being less than the distance between the sides of the bracket. The clip is made of spring wire and is in a state of tension to retain the lobes in front of the face of the bracket, thereby latching the clip in the retaining position.

To release the clip, it is pushed backwardly about its pivot moving the yoke out from under the end of the lamp. As this movement takes place, the lobes engage the sides of the bracket and exert a camming action to spread the ends, permitting the lobes to ride up on the sides of the bracket to hold the clip in released position. The clips remain in this position, permitting the lamp to be removed and replaced. When a lamp has been mounted in the sockets the clips are pulled inwardly about their pivots to place the yokes beneath the ends of the lamp. As each clip swings forward, its lobes ride off the sides of the bracket, moving toward each other to snap the clip forward into retaining position. The yoke may go beyond the groove when snapped in place but the lobes prevent the clip moving out from beneath the lamp.

It is seen therefore that the clips act as safety members to prevent the tube falling out of its fixture in case one or both its ends tend to come out of their sockets. Should the trouble be due to the spreading of the brackets, the yoke of the clip remains in the groove to prevent the tube falling out of its fixture as the distance between the end of the lamp and the bracket increases. Inasmuch as the lobes latch the clip in retaining position, the retaining action is assured. Also, the lobes riding up onto the sides of brackets when the clip is released, hold the clip in released position so that undivided attention may be given to the handling of the tubes. No tools are needed for moving the clip from retaining position to released position and as the clip remains attached to the bracket at all times it is not subject to being mislaid or lost.

The clips may be applied to brackets other than those illustrated and variations in the construction of the clips may be made without departing from the scope of the invention. It is intended therefore that all matter contained in

the above description or shown in the accompanying drawing shall be interpreted as illustrative and not in a limiting sense.

What is claimed is:

1. A tubular lamp support having a bracket provided with a socket for receiving the end of the lamp and having a spring retaining clip pivotally mounted on the bracket extending around the end of the lamp, characterized in that the clip has camming portions extending partially in front of and over the face of the bracket from each side thereof for holding the clip in lamp retaining position, said camming portions upon the clip being swung backwardly, automatically riding up onto the sides of the bracket thereby releasing the clip and thereafter engaging the sides of the bracket to hold the clip in released position to enable the lamp to be removed from or inserted in said socket.

2. A tubular lamp support having a depending bracket provided with a socket for receiving the end of the lamp and having a spring wire retaining clip pivotally mounted at its upper end on the bracket and extending underneath the end of the lamp, characterized in that the clip is bent inwardly on each side near its upper end to extend partially in front of the face of the bracket to hold the clip in lamp retaining position, said inwardly bent portions, upon the clip being pushed backwardly, automatically riding up onto the sides of the bracket to release the clip and thereafter remaining in engagement with the sides of the bracket to hold the clip in released condition.

3. A tubular fluorescent lamp support having a depending bracket provided with a socket in the face thereof for receiving contacting pins on the end sealing cap of the lamp, the sealing cap being provided with a circumferential groove, and having a spring wire retaining clip for the end of the lamp, said clip being of U-shaped construction with the yoke extending under the end of the lamp and of a radius to fit in the groove in the end cap, the legs of the clip being bent back near the upper end away from the end of the lamp and the ends being bent inwardly, the bracket being provided with aligned apertures to receive the ends of the clip to form a pivot, characterized in that said legs of the clip are also bent inwardly in front of the face of the bracket to form lobes just below the points at which they are bent back, the distance between the lobes being less than the distance between the sides of the bracket, and said clip being in a state of tension to retain the lobes in front of the face of the bracket and thus latch the clip in retaining position, said lobes, upon the clip being pushed backwardly, riding up onto the sides of the bracket to automatically spread said legs to enable the clip to be moved back out of the way of the lamp and thereafter remaining in engagement with the sides of the bracket to hold the clip in released position.

SELDEN BRADLEY SANFORD.
